Egon Spindler
ATTORNEY

UNITED STATES PATENT OFFICE

JOSEPH BLOCK, OF BROOKLYN, NEW YORK, ASSIGNOR TO NOMA ELECTRIC CORPORATION, OF NEW YORK, N. Y., A CORPORATION OF NEW YORK

ELECTRICAL DECORATIVE ILLUMINATING DEVICE

Application filed November 2, 1928. Serial No. 316,837.

This invention relates to electrical decorative illuminating devices.

It is directed to the provision of a highly ornamental unitary illuminating unit of the character described simulating a row of candles.

One of the objects of the invention is to provide a decorative illuminating unit of the character described with simple means where-
10 by a similar unit may be connected thereto and supplied by the same electrical source.

Another object of the invention is to provide a unit of the character described with neat inexpensive means for protecting and
15 covering the wiring.

A further object of this invention is to provide a compact and rugged device of the character described which shall be inexpensive to manufacture, and which shall yet be
20 highly ornamental and practical and efficient to a high degree in use.

Other objects of this invention will in part be obvious and in part hereinafter pointed out.

25 The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

35 Fig. 1 is a front elevational view of a unit embodying the invention.

Fig. 2 is a partial cross-sectional view of said unit.

40 Fig. 3 is a cross-sectional view taken on line 3—3 of Fig. 2.

Referring in detail to the drawings, the numeral 10 designates a unit embodying the invention which is here seen to comprise a row of candle simulating members 11 mounted
45 on a base 12 supported by legs 13.

The base 12 comprises an elongated board 14, made of wood or any other suitable material formed with a plurality of centrally aligned cylindrical openings 15, in the top surface thereof. Each of said openings 15

extends only partially into said base and provides a bottom wall 16. Said members 11 comprise tubular members 17, made of papier-mâché or any other suitable material for simulating candles. The lower end portions 18 of said members 17 are inserted in said openings 15 and abut said bottom walls 16. Said base 12 is further formed with reduced openings 15a substantially concentric with said openings 15, and extending to the bottom surface 12a of said base.

Electric lamp sockets 19 are fixed within the upper end portions 20 of said tubular members. Each of said sockets 19 comprises an insulating body 21 receiving a screw shell 22 and a central contact 23 insulated from said shell. Electric lamps 24, which may be of any ornamental shape to simulate candle flames are attached to said sockets 19.

Means is provided for electrically interconnecting said sockets 19, as for example in series circuit, to a source of electrical energy. To this end, conductors 25 interconnect said sockets 19 in series, as by soldering the ends 26, 27, of each of said conductors to a central contact of one socket and to the shell of an adjacent socket respectively. Said conductors 25 extend down through the tubular members 17 and openings 15a and lie against the under surface 12a of said base.

The circuit is completed by conductors 28, 28a, connected to the end sockets 19 extending down through the respective tubes 17 and openings 15a. Said conductors 28, 28a, likewise lie against the under surface 12a of the base and are joined into a duplex cable 29 adjacent one end 30 of said base. Said cable 29 may be connected to an electric plug attachment 33 adapted to be connected to any suitable electric power supply. Said plug 33 may comprise a blade plug 33a and a screw plug fitting 33b adapted for attachment to said blade plug.

Means are provided for connecting the series circuit through said sockets 19 in parallel to other circuits embodied in units similar to said unit 10. To this end conductors 35, 36 are connected as by soldered joints 35a, 36a respectively to said conductors 28, 28a. Said conductors 35, 36 also lie against the under-

surface 12a of said base 12 and are joined into a duplex cable 37 adjacent the end 38 of said base. Said cable 37 may be connected at its outer end to a blade receiving socket fitting 41. It will now be apparent that upon connecting a unit similar to unit 10 to said socket 41 as by attaching a plug 33a thereto, said unit will be connected in parallel across conductors 28, 28a. Thus said units will receive equal voltages from any power source to which the plug 33 may be attached.

The unit 10 is shown as being provided with eight "candles" 11 of varying height. Obviously any suitable number of "candles" 15 of any desired heights may be mounted on the base, depending on the ornamental effect it is desired to obtain.

It will be noted that the exposed portions of conductors 35, 36, 25, 28, and 28a which lie against the undersurface 12a of the base 12 are all in alignment with the central openings 15a.

Suitable protecting cover means is provided for said exposed portions. Said means preferably comprises a plate 45 formed with a longitudinal central channel 46 of substantially semi-circular cross sections enclosing said portions of the conductors lying against said undersurface 12a. The portions 47, 48 of the plate 45 on either side of said channel 46 lie flush against said undersurface 12a and are secured to said base 12 as by screws 49 which also secure the supporting legs 13 to said base. Said screws 49 extend through openings 50 in each corner of said plate 45. The supporting legs 13 are made of rubber or any other suitable material, and each is formed with a narrow slot 49a communicating with an opening 51 for receiving the head 52 of said screw 49, and with a passage 53 for receiving the shank of said screw. Thus the edge of a screw driver may be inserted through said slots 49a to engage the kerfs 54 in said screws for attaching both the legs 13 and plate 45 to said base 12.

The base 12 is formed with semi-cylindrical cut-out portions 31, 31a in the undersurface 12a thereof, at the end portions 38, 30 of said board, registering with said channel end portions 46a, 46b respectively. Thus the end portions 46a and cut-out portion 31 form a cylindrical passage at one end 30 of the unit 10 through which the duplex cable 37 extends, and registering portions 46b and 31a form a cylindrical passage at opposite end 30 for said cable 29. Each of said cylindrical passages is preferably plugged with an insulating bushing 32 through which said cables are threaded.

It will be seen that the unit as above described is exceedingly simple, neat and compact in construction, provides for simple connection thereto of another similar unit, 65 and for neatly and suitably covering all wir-

ing and comprises as a whole a highly ornamental illuminating unit.

It will thus be seen that there is provided a device in which the several objects of this invention are achieved, and which is well adapted to meet the conditions of practical use. 70

As various possible embodiments might be made of the above invention, and as various changes might be made in the embodiment set forth, it is to be understood that all matter herein set forth or shown in the accompanying drawing is to be interpreted as 75 illustrative and not in a limiting sense.

Having thus described my invention, I 80 claim as new and desire to secure by Letters Patent:

1. In an illuminating device, in combination, a base having a flat undersurface, a plurality of tubular members mounted thereon, lamp sockets attached to the free upper ends of said members, wiring connecting said sockets in electric circuit, said wiring having portions lying against the undersurface of said base, and means for covering said portions, said means comprising a plate 85 secured to the underside of said base and having an elongated semi-cylindrical portion receiving and covering said wiring portions and flat wing portions extending from said semi-cylindrical portion contacting said undersurface of said base. 90

2. A candle simulating unit of the character described comprising a base, a plurality of spaced tubular members mounted on said base, lamp sockets secured to the free ends of said members, electric wiring connecting said sockets in series circuit, said wiring extending through said tubular members and along the undersurface of said base and terminating in a pair of leads for attaching to a source of electric power supply, means including wiring lying against the undersurface of said base for connecting similar units in parallel across said leads and means for covering said portions of the wiring lying against the undersurface of said base, said last mentioned means comprising a plate secured to the undersurface of said base and provided with a longitudinal channel receiving and covering said wiring portions, and aligned plate portions extending outwardly from said channel contacting said undersurface of said base. 100

3. In an illuminating device, in combination, a base having a flat undersurface, a plurality of tubular members mounted thereon, lamp sockets attached to the free upper ends of said members, wiring connecting said sockets in electric circuit, said wiring having portions lying against the undersurface of said base, and means for covering said portions, said means comprising a plate secured to the underside of said base and having an elongated channel portion receiv- 115 120 125 130

ing and covering said wiring portions, flat wing portions extending from said channel portion contacting said undersurface of said base, and legs on the underside of said base for resting the device on a support.

5 In testimony whereof I affix my signature.

JOSEPH BLOCK.
